United States Patent Office

Des. 181,442
Patented Nov. 12, 1957

181,442

MOTOR MOUNT

Albert C. Reckman, St. Bernard, Ohio

Application May 13, 1955, Serial No. 35,975

Term of patent 14 years

(Cl. D26—5)

Fig. 1 is a front perspective view of a motor mount, showing my new design.

Fig. 2 is a bottom view thereof.

Fig. 3 is a rear view thereof.

I claim:

The ornamental design for a motor mount, as shown.
